DESIGN FOR A TRANSPARENT PLASTIC KNIFE

Herbert R. Talbot, Ridgewood, N. J., assignor to
Columbia Protekosit Co., Inc., Carlstadt,
N. J., a corporation of New Jersey

Application June 11, 1941, Serial No. 101,394

Term of patent 7 years

To all whom it may concern:

Be it known that I, Herbert R. Talbot, a citizen of the United States and resident of Ridgewood, in the county of Bergen and State of New Jersey, have invented a new, original, and ornamental Design for a Transparent Plastic Knife, of which the following is a specification, reference being had to the accompanying drawing, forming a part thereof, and of which Figure 1 is a front view of a transparent plastic knife showing my new design, Fig. 2 is an end view thereof on the line 2—2 of Fig. 1, Fig. 3 is a top edge view thereof, Fig. 4

is a bottom edge view with part of the blade removed, Figs. 5 and 6 are sectional views taken on the lines 5—5 and 6—6 respectively, of Fig. 1.

The front and rear faces of the handle are identical, and the front and rear faces of the blade are identical except that the fluting on the one face is offset relatively to the fluting on the opposite face as shown.

I claim:

The ornamental design for a transparent plastic knife, substantially as shown and described.

HERBERT R. TALBOT.
